[57] **CLAIM**

The ornamental design for a poultry neck slitter guide, as shown and described.

DESCRIPTION

FIG. 1 is a side elevational view of a poultry neck slitter guide, showing my new design;

FIG. 2 is a top plan view thereof;

FIG. 3 is a right end elevational view thereof.

The broken line disclosure of the poultry neck slitter in FIG. 1 is for illustrative purposes only and forms no part of the claimed design.
